US00D963056S

(12) **United States Design Patent** (10) Patent No.: **US D963,056 S**
(45) Date of Patent: ** Sep. 6, 2022

(54) **ACCESSORY FOR SPINNING TOP TOY**

(71) Applicant: **TOMY COMPANY, LTD.**, Tokyo (JP)

(72) Inventors: **Tabito Kurosaka**, Tokyo (JP);
Toshinobu Ishii, Saitama (JP)

(73) Assignee: **TOMY COMPANY, LTD.**, Tokyo (JP)

(**) Term: **15 Years**

(21) Appl. No.: **29/749,182**

(22) Filed: **Sep. 3, 2020**

(30) **Foreign Application Priority Data**

Mar. 3, 2020 (JP) 2020-004175

(51) **LOC (13) Cl.** **21-01**

(52) **U.S. Cl.**

USPC **D21/460**

(58) **Field of Classification Search**

USPC D21/454, 455, 459, 460-464, 385,
D21/436-443

CPC .. A63H 1/00-10; A63H 1/12; A63H 1/22-26;
A63F 9/16; A63F 5/041

(57) **CLAIM**

The ornamental design for an accessory for spinning top toy, as shown and described.

DESCRIPTION

FIG. 1 is a front elevational view of the accessory for spinning top toy, showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a front, right-side, top perspective view thereof;

FIG. 8 is a rear, left-side, bottom perspective view thereof;

FIG. 9 is a front, right-side, top disassembled perspective view thereof; and,

FIG. 10 is a rear, left-side, bottom disassembled perspective view thereof.

The broken lines depict parts of the accessory for spinning top toy that form no part of the claimed design.

1 Claim, 10 Drawing Sheets
